US00D565161S

(12) **United States Design Patent** (10) **Patent No.:** **US D565,161 S**
(45) **Date of Patent:** **** Mar. 25, 2008**

(54) **AIR PURIFIER**

(75) Inventor: **Kenneth David Harris, Jr.**, Hollis, NH
(US)

(73) Assignee: **Brookstone Purchasing, Inc.**,
Merrimack, NH (US)

(**) Term: **14 Years**

(21) Appl. No.: **29/240,929**

(22) Filed: **Oct. 20, 2005**

(51) LOC (8) Cl. **23-04**

(52) U.S. Cl. **D23/364**

(58) Field of Classification Search **D23/355,**
D23/364-5; 55/467, 471-2, 521

See application file for complete search history.

CLAIM

I claim the ornamental design for an air purifier, as shown and described.

DESCRIPTION

FIG. 1 is a frontal plan view of the present invention.

FIG. 2 is a rear plan view of the present invention.

FIG. 3 is a side plan view of the present invention.

FIG. 4 is a top plan view of the present invention.

FIG. 5 is a bottom plan view of the present invention; and,

FIG. 6 is a perspective view of the present invention.
